CLAIM

The ornamental design for a wall socket extender, as shown and described.

DESCRIPTION

FIG. 1 is a front perspective view of a wall socket extender with unclaimed sockets facing a forward direction;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top view thereof;

FIG. 7 is a bottom view thereof;

FIG. 8 is a front perspective view of the wall socket extender thereof with unclaimed sockets facing an upward direction;

FIG. 9 is a front perspective view of the wall socket extender thereof with alternative unclaimed sockets facing a forward direction;

FIG. 10 is a front perspective view of the wall socket extender thereof with alternative unclaimed sockets facing an upward direction;

FIG. 11 is a front perspective view of the wall socket extender thereof with alternative unclaimed sockets facing a forward direction; and,

FIG. 12 is a front perspective view of the wall socket extender thereof with alternative unclaimed sockets facing an upward direction.

The broken lines in the drawings illustrate portions of the article that form no part of the claimed design.
